L. B. & N. GOLDBERG.
FILM REEL.
APPLICATION FILED JAN. 10, 1917.

1,247,260.

Patented Nov. 20, 1917.

UNITED STATES PATENT OFFICE.

LOUIS B. GOLDBEIG AND NATHAN GOLDBEIG, OF DENVER, COLORADO.

FILM-REEL.

1,247,260.

Specification of Letters Patent. Patented Nov. 20, 1917.

Application filed January 10, 1917. Serial No. 141,709.

To all whom it may concern:

Be it known that we, LOUIS B. GOLDBEIG and NATHAN GOLDBEIG, citizens of the United States, residing at Denver, Colorado, in the city and county of Denver and State of Colorado, have invented certain new and useful Improvements in Film-Reels; and we declare the following to be a full, clear, and exact description of the invention, such as will enable others skilled in the art to which it appertains to make and use the same, reference being had to the accompanying drawings, and to the characters of reference marked thereon, which form a part of this specification.

Our invention relates to improvement in reels more especially adapted for holding moving picture films during the operation of the moving picture machine, our object being to provide a construction which is both simple and economical and which shall efficiently perform the function of a reel of this character.

Our novel features relate more particularly to the means for securing the duplex spring member mounted on the hub of the reel, in place and in operative relation, the construction of the hub being such that the extremities of the film-holding spring may remain straight or in the normal curve of the body portions of the device as distinct from a construction in which these extremities are curved upwardly. In constructions where the extremities of the spring are curved upwardly for the purpose of facilitating the attachment of the film extremity of the spring, these spring extremities are very liable to injure the film by breaking or forming holes in one or more of the convolutions of the film. In our improved construction the straight or normally curved extremities occupy positions over recesses or openings in the hub of the reel, these recesses or openings giving the operator an opportunity to insert his finger for the purpose of lifting the spring member sufficiently to attach the end of the film. Another feature of novelty consists in a spring locking key for maintaining the duplex film holding spring in place upon the hub.

Having briefly outlined our improvements we will proceed to describe the same in detail, reference being made to the accompanying drawing in which is illustrated an embodiment thereof.

In this drawing:

Figure 1 is a sectional view of our improved reel, the section being taken on the line 1—1, Fig. 3, one of the heads or end disks of the reel being shown complete.

Fig. 2 is a section taken on the line 2—2, Fig. 1, viewed in the direction of the arrow.

Fig. 3 is a section taken on the line 3—3, Fig. 1, looking toward the left.

Fig. 4 is a section similar to Fig. 1 but showing the duplex spring member or clip in a detached position. This view also shows a slightly modified form of construction.

Fig. 5 is a detailed view of the key employed.

The same reference characters indicate the same parts in all the views.

Let the numeral 5 designate the reel, considered in its entirety, and composed of two end disks or heads 6 arranged on opposite sides of a spacing hub 7 which is secured to the heads in any suitable manner as by the employment of short lugs 8 formed on the hub and inserted in perforations or slots formed in the two heads and clenched on the outside. It is evident that these heads may be connected with the hub in any suitable or desirable manner.

The hub itself is cylindrical in shape, its extremities which are normally open, being approximately closed by the adjacent head plates 6. As shown in the drawing, the heads are centrally perforated to receive a centrally located tube 9 whose opposite extremities are upset to secure the tube in place upon the heads.

The hub is provided, at a suitable location centrally between the two heads, with an opening 10 adapted to receive the central inwardly offset part 12 of a spring clip 13 having members 14 extending in opposite directions from the part 12. The offset part 12 is adapted to enter the opening 10 and when in position as shown in Figs. 1, 2 and 3, the offset part 12 extends slightly below the wall of the hub or inwardly therefrom, leaving a space between the offset and the wall of the hub for the introduction of a spring locking key 15, one extremity of which is bent as shown at 16 forming a projection extending approximately at right angles to the body member of the key. The opposite end 17 of the key is bent slightly

inwardly to facilitate its insertion or introduction into the space between the offset 12 and the wall of the hub, while between the extremities 16 and 17, the key is bowed 5 slightly downwardly or inwardly, as shown at 18, in order to exert an inward pressure on the offset 12, whereby the bend 19 of the key and the adjacent part of the extremity 16, are caused to enter a recess 20 formed in 10 one of the heads 6 which is cut as shown at 21, after which a lip 22 is pressed outwardly forming a recess of sufficient depth to receive the bend 19 of the key, the part 16 being allowed to enter the recess far enough 15 to lock the key securely in place against removal, after it has once been inserted. It will be understood that there is no necessity for removing this key except when the duplex spring clip 13 is broken, and when this 20 occurs, it is an easy matter to remove the locking key for the purpose of applying a new spring clip. The locking key may be used indefinitely since there is practically no wear upon it, neither is there any tendency 25 to break it. Consequently it may be employed with an indefinite number of spring clips, the latter being the only feature of the device upon which there is any particular wear or tendency to breakage. 30 The free extremities 26 of the spring clips lie in the same curve as the members 14 thereof and occupy positions above recesses or depressions or openings, which gives the operator an opportunity to insert the end 35 of his finger for the purpose of lifting the extremity 26 of the clip for the purpose of connecting the end of the film therewith, thus avoiding the necessity of providing upwardly or outwardly turned ends for this 40 purpose. Our construction, as heretofore stated, is exceedingly advantageous by reason of the fact that there is no tendency to break or injure the film since there is only the thickness of the metal of which the duplex spring clip is composed which extends 45 beyond the outer surface of the hub, thus allowing the convolutions of the film as it is wound on the reel, to lie practically flat or parallel with the wall of the hub. It is evident 50 that either depressions 23 or openings 24 formed in the hub will answer the purpose, hence it will be understood that the invention is not limited to any particular form, whether it be an opening formed by 55 cutting out the metal or a depression or recess formed by pressing a portion of the metal inwardly at proper locations adjacent the free extremities 26 of the duplex spring clip. 60 From the foregoing description the use and operation of our improved film reel will be readily understood. After the heads and the hub have been assembled, the duplex spring clip is applied to the hub by introducing its offset part 12 into the opening 10,

after which the extremity 17 of the spring key 15 is inserted in an opening 25 of one of the heads 6, the said opening being formed by cutting the metal as shown at 21 and pressing the portion 22 thereadjacent, outwardly. After the end 17 has been inserted in this opening, the key is pressed inwardly through the hollow of the hub and into the space between the offset part 12 and the inner surface of the wall of the hub, the pressure on the bent end 16 of the key continuing until this end 16 occupies a position directly opposite the recess 20 of the adjacent head 6. As soon as this occurs the bend 19 and the extremity 16 of the key will spring automatically into the recess 20, whereby the key is locked against removal as long as the spring clip remains intact. It will be understood that the opening 25 below the free edge of the offset part 22 is slightly lower 85 or nearer the center of the hub than the space between the offset 12 and the inner surface of the wall of the hub. Furthermore, as the key 15 is bowed slightly inwardly as shown at 18, there will be two 90 forces acting to cause the bent end 16 of the key to enter the recess 20, one being the tension under which the key is placed by virtue of the engagement of its bowed part 18 with the offset part 12 of the spring, and the 95 other being the fact that the opening 25 is slightly below the space between the offset 12 and the inner surface of the hub which the inner portion of the key enters.

After the parts are assembled as heretofore explained, it will be understood that the operator may insert the end of a finger in the depression 23 or the opening 24, and lift the end 22 of the spring clip for the purpose of connecting the end of the film therewith.

Attention is called to the fact that each of the heads 6 is provided with an opening 25 and an outwardly extending housing member 22 forming a recess 20 to receive a portion of the outer end of the locking key. By virtue of this construction the key may be inserted from either side of the reel. Of course, when the aforesaid features of one head are utilized, the corresponding features of the other head are idle. The duplicating of said features in the two heads is simply for the convenience of the operator.

Attention is called to the fact that while the key 15 is normally locked against accidental removal, it may be removed by the use of a pair of pliers even when the duplex spring clip 13 remains intact, if for any reason it may be desirable or necessary to do so. This could be done by grasping the exposed projection or the exposed part of the projection 16 by the jaws of the pliers and pulling inwardly toward the axis of the reel which would result in springing the key 130

sufficiently to enable the operator to then remove it by an outward pull.

Having described our invention what we claim is:

5. 1. A reel of the class described comprising two heads, an interposed hub, one of the heads having an opening, the hub also having an opening, a clip having an offset part entering said opening in the hub and a key 60 passing through the opening in the head and engaging the offset of the clip in securing relation.
10. 2. A reel of the class described comprising a pair of heads, an interposed hub, one 65 of the heads having an opening, the hub also having an opening, a duplex spring clip having an offset part arranged centrally of its length said part entering said opening in the hub, and a key passing through 70 the opening in the said head and engaging the offset of the clip adjacent the opening in the hub.
15. 3. A reel comprising two heads, an interposed hub to which the heads are secured, 75 one of the heads having an opening and also provided with a housing part extending outwardly therefrom adjacent said opening, the latter extending slightly inwardly toward the axis beyond the inner edge of the 80 housing part, the hub also having an opening, a clip having an offset part entering said opening and a key passing through the opening in the head and engaging the clip, the outer extremity of the key abutting 85 against the said housing of the head.
20. 4. A reel comprising two heads, an interposed hub to which the heads are secured, one of the heads having an opening and also provided with a housing part extending outwardly therefrom adjacent said opening, the latter extending slightly inwardly toward the reel axis beyond the inner edge of the housing part, the hub also having an opening, a clip having an offset 90 part entering said opening in the hub and a key passing through the opening in the hub and engaging said clip, the outer extremity of the key abutting against said housing of the head and the outer extremity 95 of said key having a part extending approximately at right angles to the body of the key, said last named part projecting inwardly toward the reel axis from the inner edge of the housing when the key is in place.
25. 5. A reel of the class described comprising a pair of heads, an interposed hub to 100 which the heads are secured, one of the heads having an opening and a housing part extending away from the opening, the latter extending inwardly slightly beyond the free edge of the housing, a clip having an offset part entering the opening in the hub, and a key passing through the opening in the head and engaging the offset of the clip, the outer end of the key abutting against 105 said housing, the said key having a part inwardly bowed between its extremities.
6. A reel comprising a hub, two heads applied to the opposite ends of the hub, the latter having an opening, one of the heads also having an opening, a clip having an offset part entering the opening in the hub and a key passing through the opening in the said head and having an inwardly bowed part engaging the offset part of the clip.
7. A reel composed of a hub and heads arranged on opposite sides thereof, the hub having an opening, a clip having an offset part entering said opening and secured therein, the hub being shaped beneath the free extremity of the clip to permit the introduction of the finger to lift the extremity of the clip for the purpose set forth.
8. A reel comprising two heads, an interposed hub and a duplex clip applied to the hub and extending part way around the same, the hub having openings adjacent the free extremities of the clip and the said clip extremities overlying but not projecting into the respective openings.
9. A reel comprising a hub and a pair of heads spaced by the hub, a duplex spring clip having a centrally located offset, the hub having an opening which said offset engages, means for securing the clip in place on the hub, the latter having depressions beneath the free extremities of the clip.
10. A reel whose hub is equipped with a clip, the hub having a cavity beneath the free extremity of the clip, and open below and beyond the latter for the purpose set forth.
11. A reel whose hub is equipped with a clip, the surface of the hub being open beneath the free extremity of the said clip.
